UNITED STATES PATENT OFFICE.

HENRY F. MOORE, OF CHICAGO, ILLINOIS, ASSIGNOR, BY MESNE ASSIGNMENTS, TO
W. S. SAITER, OF CHICAGO, ILLINOIS.

COMBINED STOKER AND GRATE.

1,246,639.

Specification of Letters Patent Patented Nov. 13, 1917.

Application filed February 1, 1913, Serial No. 745,638. Renewed April 18, 1917. Serial No. 163,041.

To all whom it may concern:

Be it known that I, HENRY F. MOORE, a citizen of the United States, and a resident of Chicago, in the county of Cook and State 5 of Illinois, have invented certain new and useful Improvements in Combined Stokers and Grates, of which the following is a specification.

This invention relates to a device which 10 is used as a grate to the fire box of boilers and also as an automatic or manually operative stoker.

The object of this invention is to obtain a device which may be installed in the fire 15 box of a steam generator, and by means of which the fuel, generally coal, which is automatically supplied thereto may be consumed, as the same is required to maintain a determined pressure of steam in said generator; to obtain a device which may be automatically stoked, when desired, or which will permit the stoking thereof at stated intervals when the stoking mechanism is in operative position; to obtain good combustion 20 of the fuel which is on said grate and prevent the formation of any considerable quantity of smoke; and to obtain a device which will not be burned out by the fire, thereon. A further object is to obtain a 25 device which is not expensive in construction; which is easily installed and usable in a large variety of differently constructed heating and steam generating plants; which requires but little care and attention; which 30 does not require a person to be particularly skilled in the art to operate it; which is durable, not liable to break or get out of order; and which is economical relative to the quantity of fuel which is required to 35 obtain a desired result. Additional objects 40 are set forth in the specification and claims.

In the drawings accompanying and forming a part hereof Figure 1 is a longitudinal section of a water tube boiler under which 45 a device embodying this invention is illustrated as installed, said section being taken on the center line of said device. Fig. 2 is a top plan view of the device, showing the walls off the fire box of said boiler in 50 horizontal section. Fig. 3 is a front elevation of a boiler front and of the operating mechanism of the device which is located outside of said front. Fig. 4 is a side elevation of the operating mechanism which is illustrated in Fig. 3, showing the upper end of the device. Fig. 5 is a side elevation 55 of a cam forming an element in the operating mechanism of the device. Fig. 6 is a front elevation of the lower end of a lever which forms an element in said operating 60 mechanism. Fig. 7 is a side elevation of the lever which is illustrated in Fig. 6. Fig. 8 is a top plan view of a sliding member which forms an element of said operating mechanism. Fig. 9 is a side elevation of 65 said sliding member, and Fig. 10 is a front elevation thereof. Fig. 11 is a side elevation of an additional sliding member and of a hook which is pivoted thereon, and Fig. 12 is an elevation of the sliding member which is illustrated in Fig. 11. Fig. 13 is a sectional view, on line 13—13 of Fig. 14, viewed in the direction indicated by the arrows, and Fig. 14 is a front elevation of the guide way which is illustrated in section in Fig. 13. Fig. 15 is a top edge view 70 of the supporting member of the device, and Fig. 16 is a side elevation of said supporting member. Fig. 17 is a top edge view of a pusher forming an element of 75 the device, and Fig. 18 is a side elevation of said pusher, with a movable cleaner and connecting rod, indicated by broken lines, attached to said pusher. Fig. 19 is a top edge view of the connecting rod which is 80 indicated by broken lines in Fig. 18, and Fig. 20 is a side elevation of said connecting rod. Fig. 21 is a section of a supporting 85 angle iron which forms an element in the device, viewed on line 21—21 of Fig. 22, in 90 the direction indicated by the arrows, and Fig. 22 is a side elevation of said supporting angle iron. Fig. 23 is a top plan view 95 of a hollow plate forming the horizontal member of the grate of the device, and Fig. 24 is a section of said hollow plate on line 24—24 of Fig. 23, viewed in the direction indicated by the arrows. Fig. 25 is a top plan view of a movable cleaner forming an element of the grate of the device, and Fig. 26 is a section of said movable cleaner, on line 26—26 of Fig. 25, viewed in the direction indicated by the arrows. Fig. 27 is a side elevation of one of the movable cleaners of the grate of the device. Fig. 28 is an enlarged section of said movable cleaner 100 on line 28—28 of Fig. 25, viewed in the direction indicated by the arrows. Fig. 29

is an elevation of a portion of the end of said movable cleaner, on an enlarged scale. Fig. 30 is an elevation of the hollow plate which is illustrated in Figs. 23 and 24, with an additional one of said hollow plates indicated by broken lines, and an elevation of a movable cleaner in a retracted position relative to said hollow plate, with said cleaner indicated by broken lines in an advanced position. Fig. 31 is a front elevation of one end of the several parts which are illustrated in Fig. 30.

A reference character applied to designate a given part indicates said part throughout the several figures of the drawing wherever said character appears.

X is the front wall of a boiler, and X' the doors to said front wall. Y, (Fig. 1) are the water tubes and Y' a head in communication with said tubes. Z is the bridge wall of the fire box of said boiler.

A (Figs. 15 and 16,) are supporting members of the device, which supporting members are rigidly secured in the side walls of the shell of the boiler under which the device is installed. Supports A are respectively provided with horizontal tables a, ribs a' on the inner side thereof, (the upper surface of said ribs also being horizontal), bolt holes a'', journal bearings A', and vertical portions, or risers, A''. B are hollow plates which are respectively placed on the tables a of supporting members A, and form the fuel supporting members of the grate of the device. b, b, represent partitions in plates B and are arranged to obtain passage ways b', (see Figs. 1 and 23). b'' represents the inlet to passage way b', and b''' the outlet. C represents short pipes or tubes which are attached to inlets b'' to discharge into said passage ways b'. Pipe or tube C which discharges into the inlet b'' and passage way b' of the lower one of the plates B, (Fig. 1), is attached to the discharge end of supply pipe C', while the remaining ones of said pipes or tubes are attached to the upper side of the several plates B so as to be in communication with the outlets b''' of the next lower plates and the inlets b'' of the next higher plates. The tube or pipe C from the highest plate B discharges into the chamber C'', which chamber is provided with the outlet C'''.

A continuous water way is thus provided for the flow of water from supply pipe C' through pipes C, and passage ways b' in the several plates B to the chamber C'', from which said water is discharged by outlet C''' to any desired place, and burning of said plates B by the burning fuel thereon is prevented.

D, D, represent movable members of the device, and D' a rocking shaft. Members D are mounted on supports A. Shaft D' is in journal bearings A'. A'' are the vertical

edges of supports A, and I term them risers. d represents a link which is pivotally attached at one end thereof to movable member D and at the other end to one of the arms of bell crank d'. Bell crank d' is rigidly attached to shaft D'. Movable member D is provided with slots d'', and D'' are bolts which extend through the slots d'' and into apertures a'' in supports A. It is by means of these bolts in said slots that members D are mounted on supports A, as hereinbefore stated, and the movement of said members D is permitted by said slots. E, E, represent additional members of the grate of the device. Members E rest movably on the ribs a' of supporting members A. Said members E are movable from the retracted position in which they are shown in Figs. 1, 4 and 30 by full lines, to the advanced position thereof which is indicated by broken lines in said figures, and said movement is obtained by connecting links e to said movable members and to members D.

It will be noted that by rocking the shaft D', the bell crank d' and members D, are moved from the retracted position thereof which is shown by full lines in Figs. 1 and 4, into the advanced position which is indicated by broken lines in said figures and thereby said members E are forced forward between said risers A'', and by said forward movement the members E are moved on to the upper surface of members B and partially over the same; and by said forward movement of the members E some of the fuel which is being consumed on said plates B is pushed off therefrom and on to the next lower plates. And further, the ashes and clinkers, if any, which are obtained from the combustion on the grate are ultimately pushed from the lowest plate B on to plate F, (see Fig. 1).

Members E are provided with apertures E', through which air to support combustion flows when said members are moving forward and back on to the plates B and between the risers A'', as hereinbefore described.

When said members E are in the retracted position which is illustrated in Fig. 1, in full lines, the water cooled members B are interposed between them and the burning fuel, and air to support combustion of said fuel flows in front of said members E, (through the space between said water cooled members) and said air tends to prevent over-heating of said members.

Movable plate F is mounted on the angle irons f, f. Angle irons f are rigidly secured in place in the ash pit of the boiler under which the device is installed. F' are handle bars which are attached to said plate F and by means of which said plate is retracted from the position in which it is shown in

Fig. 1; and when so retracted the material thereon is discharged therefrom into said ash pit.

5 G are pivotally mounted members which prevent the movable members E from carrying fuel back therewith, while said members are being retracted from their extreme forward position, and I therefore term these members cleaners or scrapers. g are the bearings in which members G are pivoted and are secured to the under side of stationary members b, see Fig. 30.

H is a fuel supply trough. When fuel such as coal which has been properly broken 15 up, (and exceedingly fine coal may be used with this device for fuel), is stored in trough H the forward movement of the upper one of the members E, as above described, will force some of the fuel from 20 said trough into the fire box and on to the upper one of the plates B.

The mechanism which is particularly illustrated in Figs. 3 and 4, and detailed in Figs. 5 to 14, inclusive, is provided to automatically obtain at regular, but not too frequent intervals, a rocking of shaft D'. Briefly stated, this mechanism consists of the reciprocating head I, having hook I' rigidly attached thereto, rotating crank 25 shaft J, connection K extending from the crank j on shaft J to head I, link L, hook L' pivotally mounted on link L, lever M, cam N on shaft n, and ratchet wheel N', also 30 on said shaft n, dog or pawl O, bell crank P, and the connections to said parts which 35 are about to be described.

The head I moves, when operated, in 40 guide i, and said guide is secured to the front of the boiler. Shaft J is mounted in bearings J', and is actuated to continuously rotate by driving shaft J'', which is provided with a gear wheel j'' intermeshing with gear wheel j' on said shaft J. The connection K moves up and down, (at the lower 45 end thereof), once to each revolution of crank shaft J, and moves head I therewith. The cam wheel N is rigidly secured on shaft n, or at least to rotate therewith, and said shaft is moved with a step by step movement, by dog or pawl O, which engages with the ratchet teeth of wheel N'. Said dog or pawl O is pivotally mounted on bell crank P, and said bell crank is actuated by pin p on wheel j''. In the construction illustrated 50 55 the dog O gives one impulse to wheel N', shaft n and wheel cam N, on each revolution of the wheel j''. Additional impulses to said wheel, shaft and cam are given to each revolution of wheel j'' by putting additional pins in said wheel. The connection link L is moved upward with the head I when the hook L' thereon is forced into position to engage with the hook I', against the resilience of spring L'', and said link 60 65 is not moved by said head when hook L' is

in the retracted position in which it is yieldingly held by said spring L''. Said hook L' is forced into position to engage with hook I' by the lower end of lever M when said lever is moved by cam N, provided said lower end, (lettered m'), is in an operative position. End m' is pivotally attached to the body part of lever M by pivot m'', and said body part is pivotally mounted on pivot m. End m' can be turned on its pivot so as not to engage with the hook L', and when it is so turned the movement of head I does not move connection L or bell crank d'. When said end m' is in position to force hook L' against hook I' it is rigidly 70 75 80 maintained in place by butterfly nut M'

Where a plurality of these devices are installed under a plurality of boilers it often occurs that the crank shaft J may be extended to operate the several parts which 85 are actuated thereby, and but one driving shaft J'' is required.

Dumping plate F is manually operated whenever desired.

Shaft D' is manually operated between the 90 times of the automatic operation thereof as hereinbefore described, if necessary; and if a low fire is desired the automatic operation of said shaft is cut out by turning the end m' as hereinbefore described, in which case 95 the manual operation of said shaft is wholly relied on for the operation thereof.

R, Figs. 1, 21 and 22 is an angle iron which is attached at its ends (r, Fig. 1), to the walls X, at the lower ends of supports 100 A, (and in the ash pit). The vertical member of angle iron R serves as a cleaner to the dumping plate F when said plate is retracted, as hereinbefore described. This angle iron R also serves as a support to the 105 lower ends of said supporting members A.

I claim;

1. Stationary grate members stepped to obtain air passage ways between them, respectively, and means to support said members, in combination with movable grate members which are normally in a retracted position and adapted to be moved on to said stationary members to force fuel from said stationary members on to the movable members which are moving on to the next lower stationary members, and to be returned to said normal position, and means to force said fuel from said movable members on to the stationary members thereunder during the 110 return movement of said movable members, said means arranged to be not in contact with said movable members when said movable members are in said normal position.

2. Stationary grate members stepped to 125 obtain air passage ways between them, respectively, and means to support said members, in combination with movable grate members which are normally in a retracted position and adapted to be moved on to the 130

said stationary members of the grate to force fuel from said grate members on to said movable members, and to be returned to said normal position, and pivotally mounted scraping members retracted from said grate members, said scraping members adapted to be turned into operative position by said movable member as said movable member is

being moved forward and to force fuel on said movable members on to said stationary 10 members as said movable members are being moved back to their normal position.

HENRY F. MOORE.

In the presence of—

CHARLES TURNER BROWN,
D. D. SWEM.
